169,259

BUILDING

James A. Hogshire, Jr., Indianapolis, Ind.

Application January 19, 1953, Serial No. 23,189

Term of patent 14 years

(Cl. D13—1)

To all whom it may concern:

Be it known that I, James A. Hogshire, Jr., a citizen of the United States, residing at Indianapolis, State of Indiana, have invented a new, original, and ornamental Design for a Building, of which the following is the specification, reference being had to the accompanying drawing, forming a part hereof.

Figure 1 is a front elevational view of a building showing my new design.

Figure 2 is a rear elevational view.

Figure 3 is an end elevational view taken from the right of Figure 1, and

Figure 4 is an end elevational view taken from the left of Figure 1.

I claim:

The ornamental design for a building, as shown.

JAMES A. HOGSHIRE, JR.
